UNITED STATES PATENT OFFICE

PAUL H. LEHMANN, OF DALLAS, TEXAS

AIR EXTRACTOR AND TUBE REPAIRING TOOL

Application filed July 28, 1930. Serial No. 471,178.

This invention relates to pneumatic tires and tubes and it has particular reference to devices for repairing automobile inner-tubes and the principal object of the invention resides in the provision of a simple and inexpensive tool of such character and design that it may be inserted into a hole or rupture in the inner-tube to serve a dual purpose, that of extricating air and for marking the puncture.

Another object of the invention resides in the addition of a novel instrument with which surplus air may be extracted from the inner-tube without the necessity of removing the valve core and cap for this purpose.

Still another object of the invention resides in its peculiar construction, affording means for roughing or buffing the area about the puncture in order to insure positive adherence of the puncture repair patch and further, the invention is provided with means by which surplus cement may be scraped off, preparatory to the application of the patch.

With the foregoing objects as paramount, the invention has particular reference to its peculiar construction and other objects which will become manifest as the description proceeds, taken in connection with the accompanying drawings wherein;

Figure 1 is a perspective view of a device constructed according to the present invention.

Figure 2 illustrates a section of an inner-tube, showing the invention inserted in the puncture.

Figure 3 shows the invention applied in buffing the tube immediately about the puncture.

Figure 4 illustrates the invention applied in scraping off the surplus cement preparatory to the application of the patch, and

Figure 5 is an end elevational view of the invention as shown in Figure 1.

Continuing more in detail with the drawings, it is pointed out that the invention is shaped from a single piece of material, the peculiarly formed body affording the several utilitarian features hereinbefore mentioned, namely, the hollow pointed handle 1 which is

insertable into the rupture or puncture in the tube to be repaired.

The handle 1 extends obliquely from the body of the tool, the said body being comprised of the flattened surface 2 with upturned edges 3. It will be observed that the surface 2 is perforated at *a*. These perforations are punched downward to afford a grating surface such as shown in Figure 5 and shown in use in Figure 3. This operation is necessary usually in the application of what is generally known as cold patch in order that the cement used in such application will quickly take hold to the smooth surface of the rubber.

It is usually recommended that a considerable amount of cement be applied to the tube and after having rubbed the same into the roughened part, the superfluous cement is removed. To conveniently remove this superfluous cement the upturned edges 3 are provided with which cement is scraped from the tube, as shown in Figure 4, preparatory to the application of a patch of the desired size.

Considerable difficulty has been heretofore encountered in extracting the air contained within the tube in order to produce a flat surface for the application of the patch. Usually, the valve cap and core are removed from the valve stem or perhaps a match or other article is inserted into the valve stem to hold the valve open to enable the air to escape. This procedure is slow and very unsatisfactory and for this reason the invention is particularly useful through the medium of its pointed handle 1, for extracting the air from the tube. It is simply necessary to force the pointed end of the handle into the puncture in the manner shown in Figure 2, and after the air has been extracted, the operations hereinbefore described may be proceeded with.

Manifestly, the construction shown is capable of considerable modification, and such modification as is considered within the scope and meaning of the appended claim, is also considered within the spirit and intent of the invention.

What is claimed is:

As a new article of manufacture, a tube repairing device including a flat body having a series of perforations therein to provide an abrading surface, the side edges of said body being turned abruptly upward, a handle for said body being formed from the material of which said body is composed and extending at an angle from said body, said handle being shaped into tubular form by turning the sides of the material inwardly whereby the handle will be gradually reduced in diameter and terminate in a point.

In testimony whereof I affix my signature.
